UNITED STATES PATENT OFFICE.

WILLIAM GOLDIE, OF WILKINSBURG, PENNSYLVANIA.

METALLIC HOOP.

No. 920,319.

Specification of Letters Patent.

Patented May 4, 1909.

Application filed November 9, 1907. Serial No. 401,524.

To all whom it may concern:

Be it known that I, WILLIAM GOLDIE, a resident of Wilkinsburg, in the county of Allegheny and State of Pennsylvania, have 5 invented a new and useful Improvement in Metallic Hoops; and I do hereby declare the following to be a full, clear, and exact description thereof.

My invention relates to metallic hoops for 10 barrels, casks, tubs, kegs, and the like, and its object is to provide a hoop which will have great strength along its upper or driving edge and also be properly trussed to give strength to the hoop and to the barrel to sustain loads.

The invention has particular reference to 20 hoops for barrels for containing dry materials, such as flour, lime, etc., in which it is important to provide a hoop very light in weight and cheap, and yet sufficiently stiff to sustain the blows in driving and of sufficient truss strength; though of course it may be employed to advantage with heavier hoops for barrels containing liquid.

To these ends my invention consists in a 25 hoop composed of a metallic strip having a concentric upper or driving edge formed of a flat folded lap, it being preferred that this folded lap shall be inwardly folded, and shall be a double folded lap to increase the strength at the upper edge of the hoop and provide thickness of metal for engagement with the driving tool.

It also consists in other improvements as 35 hereinafter set forth.

In the accompanying drawing Figure 1 is a sectional view of the preferred form of hoop; Fig. 2 is a side view partly broken away of a part of a barrel showing the hoop 40 applied to the chime portion; Fig. 3 is a like view showing the hoop applied to the bilge portion of the barrel; Fig. 4 is a section on the line 4—4' of Fig. 1 showing the preferred form of joint connecting the hoop ends; and 45 Fig. 5 is a view of another form of hoop embodying the invention.

The hoop is preferably made from very thin metal such as of 28 to 30 gage, which can be cut to proper width, and the resulting 50 strips fed to proper lapping and bending machinery to shape them. It has the body portion 2, the upper driving edge 3 and the lower trussed edge 4. As shown in the drawings, the hoop is concentric; that is, is a continuous 55 circle so as to bear closely upon the barrel throughout its circumference. The upper

or driving edge is formed of a folded lap 5 which has a positive crease or reversed bend of the metal at the upper edge of the hoop, so forming a flat folded lap and providing at 60 least a double thickness of metal for driving, and preventing bending or breaking down of the driving edge under the driving blows of the driving tool. In its preferred form, I 65 employ a double folded edge, as illustrated, the metal of the edge being bent twice and folded flat, as shown, so that its actual edge is the portion 7 and the exposed lap is the portion 8, thus providing a thick driving edge for very thin metal and one which will 70 not be broken down in driving. To further strengthen the driving edge I bead the body of the strip below the edge, as at 9, thereby forming a shoulder directly under the lapped edge acting to further sustain the same 75 against the blows of the driving tool. It is preferred that the folded edge shall be on the inner side of the hoop, as shown, because it gives a neater appearance to the outer face of the hoop and further, under the strain of 80 driving enables the hoop to bind the folded driving edge close to the body of the barrel when it is driven down to place and brings all the strength of the main body of the hoop bearing upon said folded edge which is clamped 85 between the body of the barrel and the main body of the hoop, and reduces the diameter of the upper edge portion so making it conform more closely to the incline of the barrel body. I thus also provide two or more thicknesses of metal along the upper edge of the 90 hoop and thereby give to the hoop greater strength to resist bursting or outward strain while the thick lapped portion increases the truss strength of the hoop, and by binding closely around the entire circumference of the barrel, increases the truss strength of the barrel itself, all of which enables me to form the hoop of much lighter material than is usually considered necessary. In connection 95 with the outer or driving edge so strengthened I employ the lower or trussed edge 4 which, as shown, extends outwardly at or approximately at a right angle as at 11, and is then bent backwardly for a short distance 100 as at 12, the backward bend being of less depth than the height of the forward bend so that it will not contact with the body of the barrel. Such construction gives an exceedingly stiff trussed edge to the hoop not 105 liable to damage in handling and one which 110 will not cut the hands of the workmen and

which on account of the reverse edge portion, is greatly increased in truss strength and imparts to the barrel sufficient load-carrying strength where the barrels resting on their 5 bilge are piled one upon the other. According to the uses to which the hoop is put, it may be expanded or not before use, as found desirable. For chime hoop this is desirable to enable the hoops to pass easily over the 10 edge of the barrel and to be more easily driven to place.

The great strength obtained by means of the concentric folded edge and the trussed lower edge enables me to provide a hoop 15 made of very thin sheet metal which can easily be driven to place, providing a sufficiently broad and stiff driving edge for that purpose, and a hoop which is sufficiently trussed to give all the stiffness necessary and 20 strength to sustain blows. It can be rapidly and cheaply produced and enables me to hoop the barrel with less weight of metal and therefore more cheaply than has heretofore been considered practicable.

25 In Fig. 1 I have illustrated the preferred way of uniting the ends of the hoop, the hoops being cut to exact length, according to the desired diameter and their ends abutting, and the jointing strip 13 conforms to 30 the trussed upper and lower edges of the hoop riveted to the ends. As shown in the drawing, such joint strip is bent to conform to the upper lapped edge 3 and the lower trussed edge 4 and to the body portion 2. 35 Its upper portion 14 is preferably carried around the edge of the upper lap at 16 as is its lower lip portion 15 at 17, these portions extending above and below the hoop itself and by lapping on each side of the trussed 40 portions 3 and 4 giving great strength to the joint and overcoming any necessity for lapping the same. Such joint strips can be applied either by shearing them as needed and bending the piece to the desired shape while 45 punching both the joint strips and hoops themselves for the rivets, or such parts may be bent separately and if desired punched separately.

In Fig. 5 is shown another form of hoop in

which there is only the single lap of metal 50 forming the upper edge of the strip, and this lap is provided on the outer face of the strip. Such form is not, however, considered as desirable as the form illustrated in the other figures.

55 What I claim is:

1. A metallic barrel hoop formed of a metallic strip having a concentric upper or driving edge formed of an inwardly folded flat lap.
2. A barrel hoop formed of a metallic strip having a concentric driving edge formed of a double folded flat lap.
3. A barrel hoop formed of a metallic strip having a concentric driving edge formed of 65 an inwardly bent, double folded flat lap.
4. A metallic barrel hoop formed of a metallic strip having a concentric upper or driving edge formed of a folded lap and having an outwardly turned lower flange, provided with a reverse inwardly turned lip portion of less depth than the height of said flange.
5. A barrel hoop formed of a metal strip having a concentric upper or driving edge 75 formed of a folded lap, and having its body beaded in under the folded lap to give support thereto.
6. The combination of a barrel hoop formed of a metal strip having enlargements 80 at its top and bottom edges, and a jointing strip corresponding in shape to the body of the hoop and the enlargements thereof and securing the ends together.
7. The combination of a barrel hoop 85 formed of a metal strip having enlargements at its top and bottom edges, and a jointing strip corresponding in shape to the body of the hoop and the enlargements thereof and securing the ends together, said jointing strip 90 having its edges carried beyond and above and below the enlarged edges of the hoop.

In testimony whereof, I the said WILLIAM GOLDIE have hereunto set my hand.

WILLIAM GOLDIE.
